UNITED STATES PATENT OFFICE

DONALD A. NEVIN, OF WAYNESBORO, PENNSYLVANIA, ASSIGNOR TO AUTODEX CO., OF WAYNESBORO, PENNSYLVANIA, A CORPORATION OF PENNSYLVANIA

CARD-INDEXING DEVICE

Application filed July 11, 1927. Serial No. 205,000.

My said invention relates to a card indexing mechanism and it is an object of the same to provide improved means for selecting a single card or a group of cards out of a large number of cards in a tray or container with certainty and despatch. The mechanism illustrated and described herein is an improvement over that of my application, Serial No. 10,712 filed February 20, 1925, now Patent No. 1,662,534, March 13, 1928, so much only of the mechanism of that application being here shown and described as is necessary for proper understanding of the invention here claimed.

In the operation of the machine described in said application it is necessary to use either an automatic releasing mechanism, or an audit lever located at the right-hand side of the keyboard for the purpose of releasing the positioning keys and elevating the depressed card-holders to expose the card or cards which have been mechanically selected. The automatic release adds considerably to the expense of the device and the use of the audit lever slows up the operation of the machine. An object of my invention is to provide means for selecting cards without incorporating the automatic release mechanism or operating the audit lever, thereby greatly reducing the cost of and increasing the speed of operating the machine.

Another object is to provide means for elevating cards in small groups, so that a desired card may be selected from such a group by means of visible top tabs. This makes it feasible to use by this means all of the tabs or projections on the lower margin of the cards for classification, and for cross-indexing purposes.

Still another object is to provide means operative in conjunction with the return key in such a manner that after a number of cards have been elevated, some of them can be returned and others retained.

Referring to the drawings, which are made a part of this application and in which similar reference characters indicate similar parts;

Fig. 1 is a perspective of a part of my device,

Fig. 1^a, an elevation of an index card, Fig. 2, a front elevation, partly in section, of parts of the operating mechanism, Fig. 3, a similar figure in a different plane, Fig. 4, a similar figure in still another plane,

Fig. 5, a side elevation, partly in section, showing certain operating devices,

Fig. 6, a section on line 6—6 of Fig. 7 showing a feature of my improvements,

Fig. 7, a side elevation of the same, partly in section, and,

Fig. 8, an end elevation of a card tray shown in Fig. 1 with the front end of the tray and certain other parts omitted, illustrating certain improved features in elevation.

Figures 1 to 5 illustrate features claimed in my application above referred to, including a card tray 10 removably supported on a mechanism case 11, having at its end next the operator an upward extension with a front plate 12, a rear plate 13, a keyboard 14, a bottom plate 15 and a guide plate 16.

Slidable group-selecting keys 17 (Figs. 1 and 2) in the front row of the bank on the keyboard are held up by springs 18 and are connected by links 19 to rockarms 20, on longitudinal hollow shafts 21 journaled in cross-plates 22. Shafts 21 have rockarms 23 connected by links 24 to tie rods 25 (only one of which is shown in Fig. 2) the tie rods being attached to rockarms 26 depending from hollow pivot bars 27 journaled in brackets 28. The pivot bars 27 carry laterally extending arms supporting hollow lift rods 29 on which clutches 30 are borne. A release key 31 also forms part of said front row.

Sub-group selecting keys 32 (Figs. 1, 3, and 7) in the second row on the key board are normally held in the position shown by springs 33 but may be held down, when sufficiently depressed, by means of pivoted detents 32 actuated by springs 33 and adapted to engage notches at 34. The individual keys are connected by links 34 to rockarms 35 on hollow shafts 36 in a bank above the bank of rods 21 (Fig. 3) and similarly supported. Rockarms 37 on said shafts 36 are connected by links 38 to clutches 30.

The index cards 38^a are placed by sub-groups of limited number in card-holders which card-holders are arranged in groups A, B, C, etc., in the card tray. The card-holders as here shown may be made of sheet metal, as in my above mentioned patent with sides one of which is shown at 39 (Fig. 4), connected at the lower left-hand corner by stepped parts 41 and 42 with a small projection 43 between them. These parts are secured to a shoe 44 slideable on a shelf 45 (Figs. 2 and 3) by means of a lug 46 operated by arms 47 and 48 on clutch 30. At the lower right-hand corner a similar shoe (not shown) slides on a guide 50 and the sides 39 and 40 are connected by an irregular-shaped corner piece 51. The card-holders are open at the bottom to expose the bottom tabs 78, 79 on the cards. A stop rail 52 (Fig. 4) limits the angular downward and sidewise movement of the card-holders, which are guided between partitions 53 (Fig. 1) of the tray.

A bracket 54 is fixed to a side member 55 of the tray, and a bracket 56 in Fig. 8 is part 25 of a hanger plate of the tray frame.

The group-selecting keys act on the clutches to position them operatively with reference to a group such as indicated at A, B, C, etc., in Fig. 1 which may, e. g., include all surnames beginning with the corresponding initials; the sub-group selecting keys actuate selectively the operatively-positioned clutches to move a selected card-holder, (which may, e. g., include all cards having given or 35 Christian names corresponding to the key which is actuated in the second row) downward and to the right, the cards moving to the position indicated at *a* in Fig. 4 where they are arrested by stop 52, but the card-holder can be moved further down to the 40 position indicated in Fig. 4.

For isolating cards in a sub-group after such further movement of the card-holder cards such as that shown at *a* (Figs. 4 and 8) 45 are moved to the left into a position indicated at *b* on ledges of the holder, one such ledge being shown at 58 in Fig. 4 and another at 59 in Fig. 8, where they are held against return to the right by engagement of a lug 43 on 50 ledge 58 with notches 60 in the cards. A notch 59' may be provided near the right bottom corner to coact in like manner with the top of part 59. When the holder is subsequently raised by a spring or springs (as in 55 the prior patent) after release of the positioning or sub-group key the card or cards on the ledges will be lifted at once while the other cards will be lifted only after the holder rises high enough to engage them, at 60 the lower right-hand corner and at the parts of the bottom edge adjacent to notch 60, hence such selected cards will be moved higher and to the left of the others in the sub-group as at 61 in Fig. 1.

65 The means for isolating cards in a sub-

group includes selection keys 62 in the third, fourth and fifth rows on the key-board. The slide members carrying keys of these rows have cam-slots 63 which, when the keys are depressed against the force of springs 66, act 70 through pins 64 to move cam-rails 65 lengthwise, thus causing pins 71 to be lifted by cam-slots 70 to raise selection rails 67 and also, by engagement of bosses 68 with the sides of V-shaped slots in guide plates 22, tilting these 75 rails to cause them to move selected cards to the left by engagement with tabs 79 on the lower edges of the latter. The keys 62 may carry letters of the alphabet and the tabs 79 on the cards may be arranged to correspond 80 to the middle initials of names of persons. Return of the keys 62 by springs 66 will retract their cam rails 65 and by means of an elongated boss 69 at the opposite side of a rail from a boss 68 the cam rail and its 85 selection rail will be tilted back to normal position.

An additional selection is made possible by the use of rejection rails 72, 73, 74 (Fig. 4) 90 operated by retain keys 75, 76, 77 in a manner broadly similar to the selection rails, but in the opposite direction to move rejected cards to the right, back into normal position in the sub-group, the rejection rails acting on right, left and center rejection tabs 78 facing 95 in the opposite direction from tabs 79.

The mechanism so far described, but not claimed per se, permits of a close selection from a great number of cards. To avoid the expense of an automatic release, and to speed up the operation of the device by rendering it unnecessary to use the audit lever 57 for the purpose described in my Patent 1,662,534 except when a number of positioning or sub-group selecting keys 32 must be depressed due to the need to act on a large number of cards, I have provided a key-board slider 80 (Figs. 6 and 7) operated by a knob 81, said slider being guided and held in place by screws 82 sliding in slots in plate 16. Lugs 83 are suitably positioned along one edge of the slider to engage under shoulders 84 on the keys 32 when the slider is pushed in, and the distance of said shoulders from the slider is such as to arrest the downward movement of the keys before the detents 32' can engage in notches 34', thus preventing the detents from locking the keys down. When, therefore, a key 32 is depressed it will be held down by the operator until one of the selection keys 110 and one of the rejection keys have been actuated to offset and reject cards as desired 115 after which the positioning key will at once be returned by its spring.

At the right-hand side of Fig. 8 I have 125 shown a grouping rail 88. The trays are adapted preferably to hold 1,000 cards and the card-holders to hold 10 cards. In some cases it is desirable to select all the cards in a holder, and then make further manual selection there- 130

from by means of top tabs 89 instead of the bottom tabs which bottom tabs may in such case be operated by the selection rails and the rejection rails for classifying purposes such as territory, due dates, months, etc. In such cases the top tabs would correspond; e. g., to the middle initials of names of persons and the bottom tabs would be arranged to take care of other classifications such as those enumerated or such as may be found desirable.

The grouping rail extends the entire length of the tray and is guided in slots in the tray frame plates of which a part is shown at 56. The grouping rail is connected by one or more links 89 to corresponding rockarms 90 on a group-operating shaft 91. A hand-lever 92 on said shaft serves for rocking the same, said lever being held in place by notches indicated at 93 in bracket 54. It will be seen that when a card-holder has been offset as in Fig. 8, all the cards in the same are made to engage the rail at their lower right-hand corners and operation of said rail will select them all by moving them up on the ledges 58 and 59.

In place of the return rail operation of my former application, I now provide a selective return mechanism including a return key comprising a finger piece 94 on a flat bar 95 movable in a slot of a bracket 96, the key being guided by a pin 97 and held up by a spring 98. At its lower end the key is pivoted to a rockarm 99 on a shaft 100. Another rockarm 101 on said shaft has pivoted thereto one or more links 102 only one of which is shown in the drawings carrying a return bar 103 for pushing back selected cards by action on a side edge thereof. A bent shift lever 104 which is or may be guided by bracket 96 is loosely journaled on hollow shaft 100 and has a laterally extending finger 105 supporting the return bar 103. When the cards are in their elevated position actuation of return key 94 will rock shaft 100 and force bar 103 against all such as do not have a notch at 106, the cards having such a notch remaining in selected position. By moving the shift lever 104 to the dotted line position (Figure 8) the finger 105 is permitted to swing down into the dotted line position indicated carrying with it the rod 103 and can then be actuated through the return key to push back all cards except those having a side notch at 107, thus adding another degree of selectivity to those disclosed in my Patent 1,662,534 which will of course be particularly useful where cards have to be isolated in a number of card-holders, so that the previously selected number may be quickly reduced by a rejection (return) of those not wanted.

It will be obvious to those skilled in the art that the devices shown and described may be modified in many ways without departing from the spirit of the invention and therefore I do not limit myself to what is shown in the drawings and described in the specification

but only as indicated in the appended claims.

It will be noted that the card shown in Figure 1^a has a notch at the right as in my former application and for like purposes. The card has a notch at 106, as in Fig. 8 and in other respects is or may be similar to the card shown in my patent above mentioned.

Having thus fully described my said invention what I claim as new and desire to secure by Letters Patent is:

1. A card-indexing device comprising a container, cards in the container arranged in groups and sub-groups, means for selecting a group, means for selecting a sub-group in said group and moving said sub-group out of normal position, means for locking the second-named selecting means to maintain the sub-group in selected position for further selecting operations on the cards therein, and means adapted to be positioned to prevent action of said locking means, substantially as described.

2. A card-indexing device comprising a container, cards in the container arranged in groups and sub-groups, means for selecting a group, means for selectively moving a sub-group in a selected group, including separate keys for different sub-groups, means for locking the keys in actuated position to hold the sub-group in selected position for further selecting operations on the cards therein, and means adapted to be set to prevent locking of any of said keys, substantially as described.

3. A card-indexing device comprising a container, cards in the container arranged in groups and sub-groups, means for selecting a group, means movable to select a sub-group in a selected group including separate keys for different sub-groups, detents for locking said keys when fully actuated, and a slidable bar having means for engaging shoulders on said keys to prevent stitch full actuation, substantially as described.

4. A card-indexing device comprising a container, cards in the container arranged in groups and sub-groups, means for positively offsetting a selected sub-group in such a group, means for locking the sub-group in offset position during further selective operations, and means adapted to be positioned to prevent such locking action, substantially as described.

5. A card-indexing device comprising a container, cards in the container arranged in groups and sub-groups, means for positively offsetting a selected sub-group in such a group, means for locking the sub-group in offset position during further selective operations, means to move cards in said sub-group selectively in a direction opposite to the offsetting movement, and means adapted to be positioned to prevent such locking action, substantially as described.

6. A card indexing device comprising means to effect a card-selecting operation in-

cluding a series of keys, means for locking the keys in actuated position, and means to inhibit the action of the locking means, substantially as described.

7. A card indexing device comprising means to effect a card-selecting operation including a series of keys, means for locking the keys in actuated position, and means whereby actuation of the keys to such a degree as to bring the locking means into action may be prevented, substantially as described.

8. A card indexing device comprising means for effecting a card-selecting action including reciprocatory keys, detents engageable with shoulders on said keys when fully actuated, and means adapted to be set for engagement with said keys prior to full actuation to prevent operation of the locking means, substantially as described.

9. A card indexing device comprising means for effecting a card-selecting action, including reciprocatory keys, detents engageable with shoulders on said keys when fully actuated, and a bar movable into position for engagement with shoulders on the keys to stop them before the detent becomes operative, substantially as described.

10. A card-indexing device comprising a container, cards in the container arranged in groups and sub-groups, selective irregularities on said cards, means for selecting a group, means for selecting a sub-group in said group, means to isolate a card in said sub-group by acting on selective irregularities on said card, and a plurality of independent means acting on other selective irregularities of the cards for selectively returning isolated cards to the sub-group, substantially as described.

11. A card-indexing device comprising a container, cards in the container arranged in groups and sub-groups, selective irregularities on said cards, means for selecting a group, means for selecting a sub-group in said group, means to isolate a card in said sub-group by acting on irregularities on said card, a plurality of independent means acting on other selective irregularities of the cards for selectively returning isolated cards to the sub-group, and means to complete the isolation of non-returned cards by pressure on a relatively rigid part of the same, substantially as described.

12. A card-indexing device comprising a container, cards in the container arranged in groups and sub-groups, means for selecting a group, means for selecting a sub-group in said group, means to isolate one or more cards from said sub-group, and means located at one side of the tray for separating cards so isolated selectively from the others, substantially as described.

13. A card-indexing device as claimed in claim 1, in combination with separating means adapted to act on selective irregulari-

ties on the separated cards to return them toward original position in the sub-group, substantially as described.

14. A card-indexing device, comprising a container, cards in the container arranged in groups and sub-groups, means for selecting a group, means for selecting a sub-group in said group, means to isolate a plurality of cards from said sub-group, and independent means adapted to act on differently formed side edges of the cards to reject certain of the cards so isolated, substantially as set forth.

15. A card-indexing machine comprising a container for cards, means for moving cards selectively partly out of the mass in a lateral direction, and means adapted to act on selective irregularities exposed by such movement for returning certain of the cards thus selected, substantially as set forth.

16. A card-indexing machine comprising a container for cards, means for moving cards selectively laterally of the container and means adapted to act on selective irregularities exposed by such movement for returning certain of the cards thus selected, substantially as set forth.

17. A card-indexing device comprising a set of cards, means for moving cards of the set selectively endwise, and means for acting selectively on the exposed ends of certain of the cards so moved for returning them to position, substantially as set forth.

18. A device as in claim 17 said returning means including a bar extending alongside the set, and means for pressing said bar against the exposed ends of the cards.

19. A device as in claim 17 said returning means including a bar extending alongside the set, a rockshaft supporting said bar, and means for oscillating the rockshaft, substantially as set forth.

20. A device as in claim 17 said returning means including a bar extending alongside the set, a rockshaft pivotally supporting said bar, and means for swinging the rockshaft to bring the bar into operative engagement with different selective characteristics distributed along adjacent edges of said cards, substantially as set forth.

21. In a card-indexing device, a container, cards in the container arranged in groups and sub-groups, holders for the sub-groups, inclined shelves supporting said holders, rockarms for engaging said holders to move them on said shelves, means for moving the rockarms selectively into engagement with any selected holders, means for moving the engaged rockarms, means to lift all the cards in the holder to a position above the normal for further manual selection, and means for alternatively isolating cards of the sub-group selectively, substantially as set forth.

22. A card-indexing device comprising a container, cards in the container arranged

in groups and sub-groups, means for selecting a group, means for selecting a sub-group in said group, means to isolate a card in said sub-group by acting on a selective projection on said card, and means for alternatively moving all the cards of the sub-group to a relatively exposed position, substantially as set forth.

23. A device as in claim 22 in which the cards of the sub-group are moved laterally to said relatively exposed position, substantially as set forth.

24. A device as in claim 22 in which the cards of the sub-group are moved laterally and vertically to said relatively exposed position, substantially as set forth.

25. A card-indexing device comprising a container, cards in the container arranged in groups and sub-groups, means for selecting a group, means for offsetting a sub-group relatively to the remainder of said group, and means for exposing said sub-group for manual selection by a movement in the contrary direction, substantially as set forth.

26. A card-indexing device comprising a container, cards in the container arranged in groups and sub-groups, means for selecting a group, means for offsetting a sub-group relatively to the remainder of said group, means for exposing said sub-group for manual selection by a movement in the contrary direction, and means for alternatively exposing cards selectively, substantially as set forth.

27. A card-indexing device comprising a container, cards in the container arranged in groups and sub-groups, means for selecting a group, means for offsetting a sub-group relatively to the remainder of said group, means for exposing said sub-group for manual selection by a movement in the contrary direction, and means for thereafter selectively returning certain cards toward the previous position in the set, substantially as set forth.

28. A card-indexing device comprising a container, cards in the container arranged in groups and sub-groups, means for selecting a group, means for offsetting a sub-group relatively to the remainder of said group, a grouping bar extending lengthwise of the set, and means for causing said bar to press against a normal side edge of the cards of said sub-group to expose the sub-group for manual selection, substantially as set forth.

29. In a card index, a card having one or more tabs at the bottom for mechanical selection, notches at opposite sides, and a visual selection tab at the top, substantially as set forth.

In testimony whereof I affix my signature.
DONALD A. NEVIN.
